UNITED STATES PATENT OFFICE.

PHILIP N. HANSEN, OF LOS ANGELES, CALIFORNIA.

OPTICIAN'S MULTIPLIERS.

1,412,520.

Specification of Letters Patent. Patented Apr. 11, 1922.

Application filed May 26, 1920. Serial No. 384,484.

To all whom it may concern:

Be it known that I, PHILIP N. HANSEN, a citizen of the United States, residing at Los Angeles, in the county of Los Angeles and State of California, have invented new and useful Opticians' Multipliers, of which the following is a specification.

An object of this invention is to provide a novel plier by means of which an optician may perform numerous operations, for which, in the art as heretofore existing, it was necessary to employ a number of dissimilar pliers; thus requiring the artisan to change from one plier to another in the operation of conforming the spectacle bridges, frames, studs and straps to a required position and in making the bends necessary to the purpose of proper adjustment of frames and lenses.

20 An object is to provide pliers by which an optician may make various bends as above suggested without the use of any other pliers.

An object of this invention is to provide 25 a plier for the use of opticians in cases where, during the operation of making various bends, the material on which the plier is used, has heretofore been likely to escape the grip of the instrument, thus causing 30 breakage of lenses. An object is to provide a superior bridge rolling plier in the use of which the material being bent cannot slip through the jaws of the plier. An object is to prevent the usual loss from breakage

35 which is caused by using pliers heretofore known for making such bends. That is to say, heretofore an optician's bench required numerous pliers each of which was required for some specific use, and in the general

40 practice of skilled workmen with such pliers it has frequently occurred not only that lenses were broken due to insecure hold on a bridge, causing a lens to snap when the pliers slipped, but also such slipping frequently causes the pliers to cut the shank, thus weakening same to such an extent that it is oftentimes necessary to replace the damaged bridge with a new one. Or a slip of the pliers may also break the shell of gold

45 50 that covers the base metal, thus allowing corrosion and possible injury to the wearer. The breaking of such shell makes it necessary to replace the bridge with a new one.

I have discovered that these difficulties

may be overcome by means, which as will 55 hereinafter be more clearly shown, is comprised in a single simple pair of pliers; and the invention herein set forth is broadly new, basic and pioneer in that it comprises pliers having elongate taper jaws, the tip of 60 one of which jaws extends beyond the tip of the other jaw and is bent to form a detent adapted to extend in front of the tip of the other tapering jaw when the pliers are closed upon a spectacle bridge, or end piece when 65 alinement of temples is necessary, and close enough to such tip of the other jaw to intercept the part thus held and to prevent slippage of the tool from such part.

A further feature of the invention consists in constructing jaws of the character just set forth, with an open space between the bent tip and the end of the other tip when the pliers are closed upon a strap, so as to accommodate the shoulder of the strap 70 and allow the pliers to be used in widening the strap when the pliers are held in one position; and if the pliers are reversed, it may also be used to narrow the width of 75 strap in the same manner as is common 80 with bending and shaping pliers heretofore known.

This invention relates to the specific construction of the jaws of the pliers.

Other objects, advantages and features of 85 invention may appear from the accompanying drawing, the subjoined detail description and the appended claims.

The accompanying drawing illustrates the 90 invention.

Figure 1 is a fragmental side elevation of the pliers closed.

Fig. 2 is a section on line x^2 , Fig. 1, looking down.

Fig. 3 is a transverse section on line x^3-x^4 , 95 Fig. 1 looking down.

Fig. 4 is a transverse section on line x^3-x^4 , Fig. 1, looking up, the jaws being slightly open.

Fig. 5 is a perspective view of the pliers in 100 position for holding a pair of spectacles by the end piece with perfect security while lining up temple bows.

Fig. 6 is a perspective view of the pliers as they appear in position for rolling a 105 bridge.

Fig. 7 is a view of the pliers holding the bridge in another position.

Fig. 8 is a view of the pliers holding the post of a stud.

Fig. 9 is a view from the right of Fig. 8, the post being sectioned on line ω^o , Fig. 8.

5 Fig. 10 is a view illustrating the use of the pliers for widening a strap.

Fig. 11 is a view of the pliers in use for narrowing a strap.

Fig. 12 is on the scale of Fig. 10, showing 10 the inner or opposed faces of the two jaws; said jaws being detached from each other and placed side by side for comparison.

The pliers are constructed with the usual handles 1, 2 crossing each other at the usual 15 pivot 3 and terminating respectively in taper-like jaws 4, 5; said jaws being reduced from heel to tip. The jaw 4 is of a general conical form being substantially circular in cross section from heel 6 to tip 7. The jaw 20 5 is semi-conical and has a flat inner face 8 opposed to the convexity of the concial jaw 4. Said jaw 5 is of greater length than jaw 4 and the flat face 8 extends from the heel 9 to a detent lip or hook 10 which is made by 25 bending over the tip of the longer jaw 5; said hook or detent being adjacent to but spaced apart from the tip 7 of the conical jaw to form a narrow recess 11 between the tip 7 and the detent when the jaws are fully 30 closed as indicated in Fig. 1.

The jaw 4 is externally reduced near its tip as at 12 and the jaw 5 is likewise reduced at 13, thus fitting the instrument for insertion into the narrow limits of the spaces 35 into which the tips must enter in bending the strap and handling other parts of the spectacle mounting.

The face 8 and detent 10 combine to form 40 an angle that is approximately a right angle inside corner 14 slightly spaced from the tip 7 which terminates in a flat face 7' opposed to the inner face of the detent 10.

It is thus seen that in grasping any part 45 of the spectacle mounting, one side of the part grasped may be held by one or more flat surfaces; and that in grasping a part which is wider than the recess 11, it is impossible for the pliers to slip from the part thus grasped; and yet the likelihood of 50 marring the part grasped is minimized.

In rolling a bridge as indicated in Fig. 6 the round conical jaw 4 is adapted to give appropriate form to the bridge without abrading or marring the same, and there is 55 no possibility of slippage.

In grasping the post as indicated in Figs. 8 and 9, tip 7 forces the post into the angle 14 as indicated in Fig. 9, thus giving a perfect grasp upon the post without marring 60 the same.

When it is desired to widen the strap, the flat faced jaw 5 with its detent 10 is placed on the outside, and the conical jaw 4 on the inside of the strap in such position that 65 when the pliers are closed on the strap, a

shoulder of the strap will be formed closer to the post; the tip 7 cooperating with the inside corner 14 to this effect.

When it is desired to narrow the strap, the flat faced jaw 5 and its detent 10 are 70 placed inside the recess of the strap and the conical jaw 4 on the outside thereof; then by closing the pliers, the strap is bent inwardly by the tip 7.

As clearly shown in Fig. 1 the opposing 75 faces 8 and 15 are spaced apart when the tips of the jaws are engaged with each other, thus leaving a clearance between the jaws. The flat face 8 is slightly bowed from heel to tip so that the portion of the face adjacent 80 the hook 10 may be in practical parallelism with the opposing portion of the conical jaw when the pliers are closed upon a strap as indicated in Fig. 9.

I claim:

1. A pair of bridge-rolling pliers having one of its jaws cone shaped and the other provided with a flat inner face extending from heel to tip; said flat faced jaw being provided with a lip at its end to secure its hold during the operation of making various bends and adjustments.

2. A pair of pliers having one of its jaws in the form of a cone and the other a longer semi-conical jaw, formed with a flat inner 95 face, said longer jaw being bent over the end or point of the conical jaw to provide a lip or hook which will prevent slipping of the article held.

3. A pair of bridge-rolling or stud pliers 100 having a conical jaw and a semi-conical flat inner faced jaw terminating in a hook or lip, there being a space between said lip and the tip of the cone, and said jaws being externally reduced near their tips for the purpose specified.

4. Opticians' pliers comprising two taper jaws reduced from heel toward the tip, one of said jaws being conical and the other of said jaws being semi-conical and having a 110 substantially flat inner face opposed to the round inner face of the conical jaw; said substantially flat faced jaw terminating in a hook extending in front of the tip of the conical jaw; and said jaws being spaced 115 apart when the tips of the jaws are engaged with each other so as to leave a clearance therebetween.

5. Opticians' pliers having a jaw circular in cross section and a jaw having a flat face 120 opposed to the round face of the other jaw; the flat faced jaw having a hook at its tip in front of the tip of the round jaw; and said flat faced jaw being slightly bowed from heel to tip on its inner surface so that 125 the portion of the jaw adjacent the hook may be in practical parallelism with the opposing portion of the circular jaw.

6. A pair of pliers having one of its jaws in the form of a cone and the other being 130

semi-conical and having a flat face opposed to the convexity of the conical jaw; said semi-conical jaw being bent so as to form a lip or hook which extends at right angles to said flat face and is adjacent to but spaced apart from the tip of the conical jaw; said jaws being externally reduced near their tips; and said jaws being spaced apart when

the tips of the jaws are engaged with each other so as to leave a clearance therebetween. 10

In testimony whereof, I have hereunto set my hand at Los Angeles, California, this 21st day of May, 1920.

PHILIP N. HANSEN.
